UNITED STATES PATENT OFFICE.

LOUIS O. LIEBER, OF LOS ANGELES, CALIFORNIA.

PLUG AND RECEPTACLE CONNECTOR.

1,227,918.

Specification of Letters Patent.

Patented May 29, 1917.

Application filed February 3, 1916. Serial No. 76,040.

To all whom it may concern:

Be it known that I, LOUIS O. LIEBER, a citizen of the United States, residing at Los Angeles, in the county of Los Angeles, State 5 of California, have invented new and useful Improvements in Plug and Receptacle Connectors, of which the following is a specification.

This invention relates to plug and receptacle connectors, adapters and the like; and relates more particularly to a combination including my universal plug connector shown and described in my application Serial Number 68,796, filed Dec. 27th, 1915. 15 And this invention has for its object the provision of a combination wherein my plug connector is adapted for universal use.

The further objects and advantages of this invention and the structural details of the 20 preferred form of device or devices embodying this invention are explained in the following specification, reference being had to the accompanying drawings, in which Figure 1 is a side elevation showing my connector applied to an electric appliance, such as a 25 toaster, Fig. 2 is an enlarged section taken on line 2--2 of Fig. 1, Fig. 3 is an enlarged section of the plug of my connector, Fig. 4 is a section taken as indicated by line 4--4 30 on Fig. 3, and Fig. 5 is a longitudinal section showing the adapter applied to plug and receptacle, and showing the use of the adapter according to my invention.

In the drawing 10 designates an electric 35 appliance such as a toaster or the like which appliance is, according to my invention, supplied with a receptacle 11. This receptacle may be in the form of a plain metal cylinder; or it may preferably have an off-set or 40 shoulder 12 in its inner surface for engagement by a ball or other member 13 of the plug 14. The shoulder may be formed in any suitable manner, either in the manner illustrated or by a groove on the inner surface of the receptacle; or a plurality of such 45 shoulders may be formed in any such manner and spaced along the receptacle surface. The plug is shown in detail in Figs. 3 and 4, comprising a porcelain or other base 50 provided with apertures 16 for passage of wires 17, one of the wires being connected at 18 to a washer 19 at the end of the plug. This washer 19 is overhung by a flange 20 of the cylindrical plug shell 21. The shell 55 is held in place by suitable screws 22. At the end of the plug I provide the usual cen-

tral contact 23 to which the other wire 17 connects. The shell 21 has a circumferential slot 25; and the body 15 is provided with an eccentric groove 26 immediately behind the slot. The ball or other moving member 13 is adapted to move freely in this slot on the eccentric surface 26; and the surface on which the ball is supported may be the surface of the porcelain itself, or any other surface 60 may be provided if desired. When the ball is at one end of the slot it projects but very little beyond the surface of the shell 21; when at the other end of the slot it projects more beyond the surface of shell 21; so that by placing the plug in the receptacle 65 cylinder 11 and then turning the plug through the fraction of a revolution, the ball 70 frictionally engaging with the inner surface of the receptacle, the ball will be rolled from its position of little projection to its position of greater projection. The ball will 75 then be forced outwardly against the inner surface of the cylindrical receptacle 11 behind the shoulder 12, and the plug is thus 80 pressed over against the opposite side of the receptacle and is held securely in place against longitudinal removal. In order to remove the plug it is only necessary to reverse the operation.

The method of operation of the plug and its coöperation with any ordinary form of screw threaded receptacle is explained in my application herein before referred to. It will be seen that this plug is universal in 90 its use and adaptable for coöperation with any form of receptacle. The essential feature of my plug is its expansive action on movement (of rotation).

Receptacle 11 has at its base a resiliently 95 supported contact 30. This contact is held in a cage 31 and is resiliently supported by a spring 32. A screw or bolt 33 holds the cage 31, and the whole receptacle, to the appliance 10, but this means of mounting is 100 of course varied to suit circumstances. When the plug is inserted the contact 30 is pushed back until it reaches its limit of backward motion, seating on the back part of the cage 31. The ball 13 is then at or past the shoulder 105 12. Turning the plug then expands the ball against the receptacle surface, and the spring 32 will then push the contact 30 and the plug outwardly so as to seat the ball against the shoulder. When the plug is in 110 place the ball is firmly seated and a good electrical contact is made.

In the form shown in Figs. 1 and 2 the plug is provided with a shield 35, the rear end of the plug being secured in the shield at 36. This shield has an insulating lining 37 which fits over the receptacle 11, completely covering the receptacle and thoroughly insulating it from contact with the person.

In the form shown in Figs. 3 and 4 the plug 14 is not inclosed within a shield but the plug is of identical construction with that shown in Figs. 1 and 2, except that it may be provided with a ring or head 40 of some suitable insulating material. This is the form of plug shown on the free end of cord 41 in Fig. 1. It is one of the advantages of my invention that the same kind of connector plug may be used on opposite ends of the connection cord 41, it only being necessary to add the shield 35 at the end desired to be connected with the receptacle 11. This provision for identical connector plugs on opposite ends of the cord is a provision of commercial importance. Heretofore it has been necessary to provide one kind of plug for insertion in a lamp circuit socket, and to provide a different kind of connector to be attached to the electric appliance 10. With my invention, where only a small turning is required to secure the plug, I am enabled to use the same plug on opposite ends of the connector cord.

I have also provided an adapter for cooperation with the plug 14 in the same manner that receptacle 11 coöperates with the plug. In fact it will be seen that the adapter is a modified form of receptacle. The object of this adapter is to adapt a plug, in this case with its shield, for reception of any ordinary electrical connection such as a screw threaded plug or lamp base or any other similar member. That is, my adapter makes it possible to use the cord 41 not only as a connection for the particular electric appliance to which it belongs, but also makes it possible to use the cord 41 as a general extension cord. The plug 14 at one end of the cord 41 is universally adapted to be inserted in any ordinary socket, or in a receptacle of the type shown at 11; and my adapter 50 may be coöperated with the shield and plug 14 in the manner shown in Fig. 5. This adapter comprises a cylindrical receptacle portion 11^a similar to the cylindrical receptacle 11 and adapted to engage the ball 13 in the manner herein before described. The outer part of the cylinder 11^a is provided with screw threads 11^b for the reception of any ordinary plug or lamp base 60, or for the reception of my universal plug or lamp base. When the lamp is in place as shown in Fig. 5, the center end contact engages the center end contact 23 of the plug 14 the plug 14 being pushed back with its ball 13 against the shoulder 12^a by the

screwing of plug 60 into place; and the electrical circuit includes parts 11^a and 11^b between the plug 60 and the shell 21 of plug 14. The outer end of the adapter is provided with a ring 62 of hard rubber or any other suitable insulating material to protect the person in applying the adapter to the shield and plug. It will be seen that my device is thus made useful as a general extension cord.

A particular feature of this invention is its standardization of parts, a standard plug being used through all connections. This is made possible by the use of the receptacle and adapter as illustrated and described; and it is this particular combination that I now wish to claim. It will be noted that, although my plug is universal in its nature and cooperates readily with any ordinary form of socket or receptacle, yet the peculiar form of receptacle, or adapter, is applicable alone to my plug or a plug of the general nature described.

Having described a preferred form of my invention, I claim:

1. An electric connector, embodying a cylindrical plug having an outwardly movable member thereon, and a cylindrical receptacle having an endless annular shoulder around its interior surface adapted to be engaged by the outwardly movable member on the plug, said outwardly movable member embodying a ball, and means to cause the ball to move outwardly by rotation of the plug.

2. An electric connector, embodying a cylindrical plug having an exterior cylindrical shell with a circumferential slot, an eccentric surface in the plug beneath the slot, and a ball adapted to move longitudinally in the slot and on said surface, in combination with a cylindrical receptacle having an interior endless annular shoulder.

3. An electric connector, embodying a cylindrical plug having an exterior cylindrical shell with a circumferential slot, an eccentric surface in the plug beneath the slot, and a ball adapted to move longitudinally in the slot and on said surface, in combination with a cylindrical receptacle of interior diameter to fit freely over the cylindrical plug, and having an endless annular shoulder extending completely around its inner surface.

4. An electric connector, embodying a cylindrical plug having an exterior cylindrical shell with a circumferential slot, an eccentric surface in the plug beneath the slot, and a ball adapted to move longitudinally in the slot and on said surface, in combination with a cylindrical receptacle of interior diameter to fit freely over the cylindrical plug, and having an endless annular shoulder extending completely around its inner surface, said plug having a central

end contact, and a resiliently supported contact at the rear end of the receptacle adapted to press against the central end contact of the plug and adapted to thereby 5 press the ball on the plug against said annular shoulder.

5. An electric connector, embodying in combination a cylindrical receptacle having an endless annular shoulder around its interior surface, a plug adapted for free longitudinal and rotational movement in said receptacle, an outwardly movable locking member mounted on said plug and projecting beyond its surface to engage the receptacle, and means to cause the member to move outwardly by rotation of the plug.

6. An electrical connector, embodying in combination, an outer cylindrical member, an inner cylindrical member adapted for

free longitudinal and rotational movement 20 in said outer cylindrical member, one of said cylindrical members having an endless annular shoulder therearound, a movable locking member on the other of said cylindrical members projecting therefrom to engage the 25 first mentioned cylindrical member and its annular shoulder, and means to cause movement of the locking member toward and against said first mentioned member by virtue of relative rotation of the two cylindrical members.

In witness that I claim the foregoing I have hereunto subscribed my name this 28th day of January, 1916.

LOUIS O. LIEBER.
